UNITED STATES PATENT OFFICE.

JOHN D. LANE, OF BOSTON, MASSACHUSETTS.

EXTERNALLY-FINISHED PAPER TUBE AND THE METHOD OF MAKING THE SAME.

Application filed August 17, 1921. Serial No. 492,894.

To all whom it may concern:

Be it known that I, JOHN D. LANE, a citizen of the United States, residing at Boston, in the county of Suffolk and State 5 of Massachusetts, have invented new and useful Improvements in Externally-Finished Paper Tubes and the Method of Making the Same, of which the following is a specification.

10 This invention relates to tubular articles such as handles of package carriers, mailing tubes, etc. The object of the invention is to utilize waste paper and particularly paper that has been printed upon and discarded, 15 in such manner as to provide at a trifling expense a suitably strong and rigid tube, and to inexpensively finish the external surface of the tube to conceal blemishes such as printed matter on the waste paper of 20 which it is made.

The invention consists in the construction and method hereinafter described and claimed.

25 Of the accompanying drawings forming a part of this specification,

Figure 1 is a perspective view of a tube embodying the invention, showing the tube as the hand grip of a package carrier.

Figure 2 is an enlarged longitudinal section of the tube.

Figure 3 is a section on line 3—3 of Figure 2.

Figure 4 is a fragmentary sectional view illustrating the operation of grooving an 35 elongated tubular blank from which a number of finished tubes may be made.

Figure 5 is a perspective view of a strip prepared for conversion into a finished tube.

Figure 6 is an enlarged section on line 40 6—6 of Figure 5.

The same reference characters indicate the same parts in all of the figures.

In carrying out my invention the procedure may be as follows:

45 A strip 12 is cut from waste paper such as a portion of a discarded newspaper. To one end of the strip is united by a suitable adhesive a finishing extension 13 forming a finishing layer in the completed tube, and 50 of flexible sheet material such as plain paper of suitable quality to form a desirable surface coating covering the outer convolution of the strip when the latter is rolled into a plurality of convolutions forming a tube 55 wall of suitable thickness. To the inner side of the strip 12 and to the inner side of

the extension 13, I apply a coating 15 of a suitable hard-drying adhesive such as glue, which is insoluble in water, the adhesive being applied in a fluid condition to which 60 it is reduced by heat. The coating 15 terminates at a point near the end of the strip 12, opposite that having the extension 13, so that a portion 12^a of the strip is left dry, 65 said portion constituting the inner convolution of the rolled strip. The strip is then rolled while the coating 15 is soft, on a suitable mandrel, the coated side being inward, and the dry portion 12^a contacting with the mandrel, so that the adhesive does not touch 70 and adhere to the mandrel. The length of the strip is such that as many convolutions may be formed as are necessary to form a tube wall 17 of the desired thickness. The convolutions of the rolled strip are united 75 to each other by the adhesive coating 15. The extension 13 covers and adheres to the outer convolution of the strip 12, and forms the outer convolution of the completed tube, 80 said outer convolution forming a finishing coating concealing the blemishes of the strip 12. The adhesive is then allowed to harden by drying, the tube being thus completed.

It is obvious that an elongated tube or blank may be formed by the described operation, adapted to be transversely cut into a plurality of operative tubes, the width of the strip 12 and extension 13 being sufficient to form such elongated tube or blank. The elongated tube may be peripherally grooved 85 at the locations where it is to be transversely cut. Figure 4 shows a peripheral groove 20 formed by a disk 21, pressed against the tube while the latter is supported and rotated by the mandrel on which it is formed. 90 When the tube is transversely cut at the location of the groove, the finishing coating formed by the extension 13 is crimped inwardly at its ends at 13^a, as indicated by Figure 3, over portions of the ends of the 95 tube, so that the tube ends present a neatly finished appearance.

As shown in Figure 4 the inward deflection of the ends of the outer or finishing layer of the tube above referred to is initiated by the disk 21 when forming the peripheral groove 20. As the tube is severed by forcing a cutter transversely thereof through said groove the crimping action of the ends of the portion 13 is completed.

105 It will now be seen that by forming an elongated strip of waste paper into a tube 110

and applying a finishing coating to the outer convolution of the tube to conceal the blemishes of the waste paper, I provide, at an inconsiderable expense, a tube which is very desirable as the hand grip of a package carrier, or as a mailing tube. The finishing coating imparts a desirable appearance to the tube, and is adapted to receive printed or written matter, such as an advertisement 10 or an address.

If desired the finishing coating may be composed of a fluid or pasty mixture or composition spread on the outer convolution of the strip 12, and adapted when dried to form 15 a suitable external finish.

I claim:

1. A tube composed of a strip of waste printed paper, wound to form a plurality of convolutions, a hard-drying adhesive uniting convolutions and rendering the same rigid, and a finishing coating of sheet material cemented to and concealing the outer convolution of the strip and the printed matter thereon.

25 2. A tube composed of a strip of waste paper, wound to form a plurality of convolutions, a hard-drying adhesive uniting the convolutions and rendering the same rigid, and a finishing coating of sheet material cemented to and concealing the outer convolution of the strip, the ends of said coating being crimped inwardly over portions of the ends of the wound strip.

30 3. The method of utilizing waste printed paper, which consist in cutting an elongated strip from such paper, uniting a flexible finishing extension to one end of the strip, coating one side of the extension and a portion

of the same side of the strip with a hard-drying adhesive, the opposite end portion 40 of the strip being dry, rolling the strip and extension with the coated sides inward on a mandrel into a plurality of convolutions while the adhesive is soft, the dry end portion of the strip constituting an inner convolution, contacting with the mandrel, the finishing extension being thus cemented to the outer convolution of the strip, and constituting a finishing coating, and finally allowing the said adhesive to solidify by dry- 45 ing.

4. The herein described method of forming tubes, which comprises cutting an elongated strip from waste printed paper, uniting a flexible finishing extension to one end 55 of the strip, coating one face of the extension and a portion of the same face of the strip with a hard-drying adhesive, the opposite end portion of the strip being uncoated, rolling the strip and extension, with the 60 coated faces inward, on a mandrel into a plurality of convolutions while the adhesive is soft, the uncoated end portion of the strip constituting the inner convolution; and the extension being cemented to the outer convolution of the strip and constituting a finishing layer, peripherally grooving the tube thus formed, and severing the tube in alignment with each groove, whereby the ends of the outer finishing layer are crimped inward over portions of the ends of the severed sections.

In testimony whereof I have affixed my signature.

JOHN D. LANE.
